UNITED STATES PATENT OFFICE.

ALFRED L. SOHM, OF CHICAGO, ILLINOIS.

DESIGN FOR AN AUTOMOBILE RADIATOR ORNAMENT.

Application filed July 20, 1927. Serial No. 22,815. Term of patent 14 years.

To all whom it may concern:

Be it known that I, ALFRED L. SOHM, a citizen of the United States, residing at Chicago, in the county of Cook and State of Illinois, have invented a new, original, and ornamental Design for an Automobile Radiator Ornament, of which the following is a specification, reference being had to the accompanying drawing, forming a part thereof:

Figure 1 is a front elevation,
Figure 2 is a rear elevation, and,
Figure 3 is a plan view.

I claim:

The ornamental design for an automobile radiator ornament, substantially as shown.

ALFRED L. SOHM.
